(57) **CLAIM**

The ornamental design for an upper for an article of footwear, as shown and described.

DESCRIPTION

FIG. 1 is a front and medial view in perspective of an upper for an article of footwear showing our new design;

FIG. 2 is a medial side view thereof;

FIG. 3 is a lateral side view thereof;

FIG. 4 is a top view thereof;

FIG. 5 is a bottom view thereof; and

FIG. 6 is a rear view thereof.

FIG. 7 is a front and medial view in perspective of another embodiment of an upper for an article of footwear showing our new design;

FIG. 8 is a medial side view thereof;

FIG. 9 is a lateral side view thereof;

FIG. 10 is a top view thereof;

FIG. 11 is a bottom view thereof; and,

FIG. 12 is a rear view thereof.

The upper for an article of footwear illustrated in the drawings is a first embodiment showing a right-footed form of the upper for an article of footwear. Another embodiment is for the left-footed form of the upper for an article of footwear, which is a mirror image of the right-footed form, is not illustrated. The broken lines showing a footwear sole depict environmental structure that forms no part of the claim. The broken lines showing structure on the upper show portions of the article that form no part of the claim. The single lines of broken lines crossing the claimed surfaces of the upper depict portions of the article that form no part of the claim.
